UNITED STATES PATENT OFFICE

BENJAMIN H. PROUT, OF MERIDEN, CONNECTICUT, ASSIGNOR TO INTERNATIONAL SILVER COMPANY, OF MERIDEN, CONNECTICUT, A CORPORATION OF NEW JERSEY

DESIGN FOR A HOLDER FOR A BABY SPOON OR SIMILAR ARTICLE

Application filed September 3, 1932. Serial No. 44,755. Term of patent 3½ years.

To all whom it may concern:

Be it known that I, BENJAMIN H. PROUT, a citizen of the United States, residing at Meriden, county of New Haven and State of Connecticut, have invented a new, original, and ornamental Design for a Holder for a Baby Spoon or Similar Article, of which the following is a specification, reference being had to the accompanying drawing, forming a part thereof;

Fig. 1 is a front elevation of the holder showing my new design;

Fig. 2 is a top plan view of the same; and
Fig. 3 is a side view thereof.

I claim:

The ornamental design for a holder for a baby spoon or similar article, substantially as shown.

BENJAMIN H. PROUT,
